UNITED STATES PATENT OFFICE.

BRADBURY HILL, THOMAS N. SHAMBAUGH, AND LAURITZ A. LARSON, OF OSAGE, IOWA.

COPY-HOLDER.

No. 806,344.

Specification of Letters Patent.

Patented Dec. 5, 1905.

Application filed November 9, 1904. Serial No. 232,018.

To all whom it may concern:

Be it known that we, BRADBURY HILL, THOMAS N. SHAMBAUGH, and LAURITZ A. LARSON, citizens of the United States, residing at 5 Osage, in the county of Mitchell and State of Iowa, have invented a new and useful Copy-Holder, of which the following is a specification.

The invention relates to improvements in 10 copy-holders.

The object of the present invention is to improve the construction of copy-holders and to provide a simple, inexpensive, and efficient book copy-holder or marker designed to 15 be applied to large books to enable accurate copies and extracts to be made from the same and capable of being quickly engaged with and removed from a book.

A further object of the invention is to provide 20 a device of this character having an adjustable indicating device adapted to be varied in length to suit the size of a book and capable of conforming readily to the curvature of the rounded or bulged portions of the 25 leaves of a book.

Another object of the invention is to provide 30 a copy-holder having book engaging or clamping devices and adjustable and detachable indicating means capable of being readily arranged to fit a book and adapted to be quickly separated from the book engaging or clamping means to permit the leaves of a book to be freely turned.

With these and other objects in view the 35 invention consists in the construction and novel combination and arrangement of parts hereinafter fully described, illustrated in the accompanying drawings, and pointed out in the claims hereto appended, it being understood that various changes in the form, proportion, size, and minor details of construction 40 within the scope of the claims may be resorted to without departing from the spirit or sacrificing any of the advantages of the invention.

In the drawings, Figure 1 is a plan view of 45 a copy-holder constructed in accordance with this invention and shown applied to a book. Fig. 2 is a transverse sectional view illustrating the construction of the indicating device. Fig. 3 is a perspective view of one of the book-engaging devices for clamping the covers of a book. Fig. 4 is a detail sectional view showing one end of the rod and illustrating the

manner of clamping the same. Fig. 5 is a detail perspective view of the slide.

Like numerals of reference designate corresponding parts in all the figures of the drawings.

1 designates a centrally-arranged rod forming 6c a guide for the indicating means and arranged at the center of a book 2 when the same is open, as illustrated in Fig. 1 of the drawings. The rod is held by a pair of clamps 3, arranged at the top and bottom of 65 the book and connected with the same by the means hereinafter described. Although it is preferable to employ a pair of clamps, as illustrated in the accompanying drawings, yet the device may be provided with only 70 one clamp, and the same may be arranged either at the top or bottom of the book. Each of the rod-supporting clamps consists of a pair of corrugated or crimped jaws 4, forming a plurality of rod-receiving seats and extending 75 upward from the book when the same is in a horizontal or inclined position and adapted to permit the rod to be adjusted to suit the thickness of the book to which the device is applied. The upper or outer ends 80 5 of the jaws are bent outward to provide a flaring mouth or entrance to enable the rod to be readily introduced into the jaws, and the said rod may be quickly placed between the jaws and instantly removed therefrom to 85 permit the leaves of the book to be turned. The lower ends 6 of the jaws, which are resilient, are bent outwardly and are secured to a rod or bar 7, which connects a pair of book-engaging clips 8. The jaws are engaged at 90 their outer portions by a pair of springs 9, constructed of resilient metal and having lower or inner outturned ends 10, arranged on the inner or lower ends 6 of the jaws and secured to the connecting-bar 7 by fastening 95 devices 11. The fastening devices also pierce the lower or inner end 6 of the jaws and secure the same to the connecting bar or rod 7. The connecting bar or piece 7 consists of a thin strip of steel or other suitable material, 100 and the clips 8, which are arranged at the ends of the connecting bar or piece and which are adapted to engage the covers of the book, are substantially U-shaped and consist of upper straight flat jaws 12 and lower jaws 13, 105 terminating short of the outer ends of the jaws 12 and having their terminals slightly curved. The upper flat jaws are adapted to

fit against the inner faces of the covers to afford a firm support for the rod-engaging clamp. One end of the rod is reduced at 14 for engaging the adjacent clamp, and the reduction of the rod provides opposite shoulders which fit against the opposite edges of the jaws for holding the rod against longitudinal movement therein. The other clamp is designed to engage the rod at different points, whereby the device is readily adjustable to suit the size of a book. The rod receives an adjustable slide 15, consisting of a rectangular loop composed of front and back walls and top and bottom connecting walls or portions, the front and back walls being connected with circular apertures 16 to receive the rod. The slide, which is open at opposite sides, receives a pair of extensible strips or members 17 and a spring 18. The strips or members which form the indicator or marker are constructed of thin resilient material and are adapted to lie against the opposite pages of a book, as indicated in Fig. 1 of the drawings. They are extensible and are adapted to be drawn outward to arrange them to suit the size of the book to which the device is applied. The spring 18, which is provided with angularly-disposed sides, is provided with a central bend 19, forming a groove or seat for the rod. The angularly-disposed sides of the spring extend laterally of the slide and engage and hold the markers or indicating-strips against the book. The spring holds the slide in its adjustment, and it also retains the extensible indicating-strips or markers in their adjustment. The slide, with its indicating-strips or markers, is adapted to be moved along the rod, as required, and the indicating-strips or markers will enable the contents of a book to be accurately copied.

The device is especially adapted for copying records from large books, and the book-engaging means which carry the rod-supporting clamps are adapted to be quickly applied to a book. The rod which forms the guide for the indicating means may be quickly arranged in the clamps and instantly removed therefrom when it is desired to turn the leaves of a book, and the adjustable indicating-strips or markers may be readily drawn outward and moved inward to arrange them to suit the size of a book. The seats of the clamps permit the rod to be readily adjusted to suit the thickness of a book.

Having thus fully described our invention, what we claim as new, and desire to secure by Letters Patent, is—

1. A device of the class described provided with an indicator having a thin indicating-strip or marker constructed of resilient material and adapted to be flexed to conform to the configuration of a book when the same bulges at the center, and a spring engaging the indicating-strip or marker for holding the

same against a book, said indicating-strip or marker being adjustable independently of the spring for varying its length and being retained in its adjustment by the said spring.

2. A device of the class described, comprising a guide arranged to lie along the center of a book, and indicating means provided with a thin indicating member or marker constructed of resilient material and slidably connected at an intermediate point with and movable across the said guide and extending from opposite sides of the same for engaging both of the leaves of a book.

3. A device of the class described, comprising a guide, indicating means slidable on the guide and embodying an indicating-strip or marker, and a spring engaging the rod and the said indicating-strip or marker for holding the latter against a book and for retaining the indicating means in its adjustment on the guide.

4. A device of the class described, comprising a guide, and indicating means embodying indicating members or markers arranged to be moved inward and outward to vary the length of the indicating means for adjusting the same to suit the size of a book, and a spring engaging the guide for holding the indicating means in its adjustment and also engaging the indicating members or markers for retaining them in their adjustment and for holding the same against a book.

5. A device of the class described, comprising a guide, a slide movable on the guide, an indicating member or marker extending through the slide, and a spring also arranged within the slide and provided with an intermediate seat to receive the guide and engaging the indicating member or marker at opposite sides of the said guide.

6. A device of the class described, comprising a guide, a slide consisting of a loop or casting open at opposite sides and provided with apertures to receive the guide, indicating members or markers arranged within the slide, and a spring also arranged within the slide and having angularly-disposed portions engaging the indicating members or markers, said spring being provided with a central bend forming a seat to receive the guide.

7. A device of the class described, comprising a guide, indicating means adjustable on the guide, and book-engaging means having a clamp provided with jaws receiving the guide.

8. A device of the class described, comprising a guide, indicating means adjustable on the guide, and book-engaging means provided with a clamp having jaws for engaging the guide, said jaws being provided with a plurality of seats for the said guide, whereby the same is adjusted to suit the thickness of a book.

9. A device of the class described, comprising a guide, indicating means movable on the

guide, book-engaging means, and a clamp carried by the book-engaging means and provided with crimped or corrugated jaws forming seats to receive the guide.

5 10. A device of the class described, comprising a guide, indicating means movable thereon, book-engaging means, a clamp carried by the book-engaging means and having jaws receiving the guide, and springs engaging the jaws.

10 11. A device of the class described, comprising a guide, indicating means movable thereon, book-engaging means, a clamp mounted on said book-indicating means and provided with a pair of jaws having seats to receive the guide, and springs extending along the jaws and engaging the same.

15 12. A device of the class described, comprising a guide, indicating means movable thereon, clips for engaging the covers of a book, a clamp provided with jaws receiving the guide, and means for connecting the clamp with the clips.

20 13. A device of the class described, comprising a guide, cover-engaging clips, a bar connecting the clips, and a clamp extending

from the bar and provided with jaws adjustably receiving the guide.

14. A device of the class described, comprising a guide, indicating means movable on the guide, clips, each having a straight upper jaw for engaging the inner face of a cover, and a lower jaw arranged at an angle to the upper jaw and terminating short of the ends thereof, and a clamp connected with the clips and provided with jaws adjustably receiving the guide.

25 15. A device of the class described, comprising book-engaging means having projecting clamps, a guide-rod arranged on the clamps and provided with shoulders for engaging one of the same, and indicating means movable on the guide-rod.

In testimony that we claim the foregoing as our own we have hereto affixed our signatures in the presence of two witnesses.
